UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

PUMP.

1,264,116.

Specification of Letters Patent. Patented Apr. 23, 1918.

Application filed July 18, 1915. Serial No. 40,563.

To all whom it may concern:

Be it known that I, SANFORD A. MOSS, a citizen of the United States, residing at Lynn, county of Essex, State of Massachusetts, have invented certain new and useful Improvements in Pumps, of which the following is a specification.

The present invention relates to pumps of the type in which an elastic or non-elastic fluid to be pumped is sucked in at one pressure and delivered against a higher pressure by means of a second elastic or non-elastic fluid which may be termed the pumping fluid and which is discharged from a suitable nozzle or nozzles. Such pumps are commonly termed injector or ejector pumps according to the use to which they are applied.

The object of the invention is to provide an improved structure which embodies certain new principles in construction and operation discovered by me and which results in a structure which is more efficient and economical in operation than those heretofore.

I have discovered that in apparatus of this character the efficiency is greatly increased by providing a plurality of nozzles for both the pumping fluid and the fluid to be pumped, which nozzles are interspersed among each other with their ends lying in substantially the same plane, and are all designed to convert pressure into velocity. They are also advantageously arranged so that the nozzles for the pumping fluid are focused on the axis of the mixing tube into which they project and which is also the discharge tube. By this arrangement I obtain maximum entrainment effect between the pumping fluid and the fluid to be pumped.

For a consideration of what I believe to be novel and my invention, attention is directed to the accompanying description and the claims appended thereto.

One application of my invention is as an ejector pump for removing air, vapor and other gases from condensers, and in the accompanying drawing which illustrates an embodiment of my invention is shown an apparatus primarily designed for this purpose. In this connection the pumping fluid will ordinarily be steam. In such drawing Figure 1 is a sectional view thereof; Fig. 2 is a section taken on line 2—2, Fig. 1;

and Fig. 3 is a view on a smaller scale and partly in section of the invention.

Referring to the drawing, the ejector casing comprises an annular side wall 4 having a flanged admission opening 5 through which the fluid to be pumped enters, an end wall 6 having a threaded admission opening 7 to receive a pipe 8 through which the pumping fluid enters the casing, and an end wall 9 having a discharge opening 10 which has a converging wall 11 terminating in a flange 12. The end walls 7 and 9 are suitably fastened to the side wall 4 as by means of bolts 13. Inside the casing is a ledge 14, to which is fastened by bolts 15 a cup-shaped member 16. For this purpose the member 16 is provided with a flange 17. The base of the member 16 is provided with a plurality of symmetrically arranged openings 18 through which project the nozzles 19. Each of these nozzles comprises a ball-shaped head 20 having an opening 21 therethrough, and a wall 22 forming a discharge passage which is designed to convert pressure into velocity. In the present instance it is shown as a diverging passage since at the pressure at which the pumping fluid will ordinarily be provided it will take this form. The heads 20 rest on seats formed in the openings 18 and are held in place by a plate 23 having openings 24 of lesser diameter than the heads and into which the heads project. The plate is held in place by bolts 25. This arrangement forms a ball joint for the nozzles so they can be very quickly and easily adjusted to the desired angle. The member 16 and connected parts form a partition which divides the casing into two chambers 26 and 27 for the pumping fluid and the fluid to be pumped respectively. Attached to the flange 12 is a diverging pipe section 28. This, with the converging wall 11, forms a converging-diverging discharge passage. The wall 11, it will be noted, forms a smooth gradually converging passage beginning at the point indicated at 29 and terminating at the throat of the converging-diverging discharge passage. The nozzles 19 project well within the converging passage 10, and terminate in substantially the same plane. They serve to divide it up into a plurality of passages which are interspersed among the nozzles. These passages are also de-

signed to convert the pressure of the fluid to be pumped into velocity as it flows through them, and in the present instance they are shown as converging passages as 5 they take this form in the design illustrated. In other words, the walls 22 and wall 11 are designed to form the interspersed passages for both the pumping fluid and the fluid to be pumped, which passages are in each instance of a form to convert pressure into 10 velocity. The passages all terminate in substantially the same plane which is the point at which mixing of the fluids begins. This, therefore, gives in substance a plurality of 15 interspersed nozzles for both the pumping fluid and the fluid to be pumped, all of which nozzles terminate in substantially the same plane. By this improved arrangement, I obtain a conversion of more or less of the 20 pressure of the fluid being pumped in velocity before it mingles with the pumping fluid, and at the same time I also obtain a subdivision of the fluid being pumped into a plurality of streams. This gives the 25 maximum entrainment effect between the respective fluids.

The nozzles for the pumping fluid as well as passages for fluid being pumped are directed so as to focus on the axis of the converging-diverging discharge passage at 30 about the throat thereof. This gives the maximum effect between the respective fluids, tending to drive the fluid to be pumped along the pumping fluid, in an efficient manner without eddies or impact.

Since the passages for the fluid to be pumped, which immediately precede the mixing plane are arranged to convert pressure into velocity, this fluid will be more 40 readily entrained by the pumping fluid, and with less friction loss, than if there were no such velocity. Also, the pressure of the fluid being pumped will be less at the mixing plane than it was in the chamber 27. 45 That is to say, although the fluid to be pumped is to have its pressure increased, we first decrease its pressure in order to increase the efficiency of the further operations.

50 In accordance with the provisions of the patent statutes, I have described the principle of operation of my invention, together with the apparatus which I now consider to represent the best embodiment thereof; but 55 I desire to have it understood that the apparatus shown is only illustrative, and that the invention can be carried out by other means.

What I claim as new and desire to secure by Letters Patent of the United States, is,—

60 1. In an apparatus of the character described, the combination of a casing having admission openings for the pumping fluid and the fluid to be pumped, and a discharge 65

opening, and interspersed multiple passages for both fluids each of which is designed to convert pressure of the fluid flowing through it into velocity.

2. In an apparatus of the character described, 70 the combination of a casing having admission openings for the pumping fluid and the fluid to be pumped, and a discharge opening, and interspersed multiple passages for both fluids which terminate in substantially the same plane and each of which is designed to convert pressure of the fluid flowing through it into velocity. 75

3. In an apparatus of the character described, 80 the combination of a casing having admission openings for the pumping fluid and the fluid to be pumped, and a discharge passage having a gradually converging wall, and a plurality of nozzles in the casing through which the pumping fluid is discharged, 85 said nozzles all terminating in substantially the same plane within the converging discharge passage and forming passages surrounding them for the fluid to be pumped, the passages through said nozzles and the surrounding passages all acting to convert pressure of the fluid flowing through them into velocity. 90

4. In an apparatus of the character described, 95 the combination of a casing having admission openings for the pumping fluid and the fluid to be pumped, and a discharge passage having a gradually converging wall, and walls in the casing forming interspersed passages for the pumping fluid and the fluid to be pumped, all of which passages terminate in substantially the same plane within the converging discharge passage and act to convert pressure of the fluid flowing through them into velocity. 100

5. In an apparatus of the character described, 105 the combination of a casing having admission openings for the pumping fluid and the fluid to be pumped, and a discharge passage having a gradually converging wall, 110 and a plurality of nozzles for the pumping fluid designed to convert pressure into velocity, said nozzles all ending within the converging discharge passage in substantially the same plane and focused on the axis of such passage, the passages surrounding said nozzles serving to conduct the fluid to be pumped and to convert pressure into velocity. 115

6. In an apparatus of the character described, 120 the combination of a casing having admission openings for the pumping fluid and the fluid to be pumped, and a discharge passage having a gradually converging wall, and walls in the casing forming interspersed 125 passages for the pumping fluid and the fluid to be pumped, all of which passages terminate in substantially the same plane within the converging discharge passage, and act to convert pressure of the fluid flowing through 130

them into velocity, said walls being so shaped that the passages for the pumping fluid focus on the axis of the discharge passage.

- 5 7. In an apparatus of the character described, the combination of a casing, means forming a partition dividing the casing into two chambers, one of which has an opening for admitting pumping fluid, and the other 10 an opening for admitting the fluid to be pumped, said last named chamber having also a discharge passage leading therefrom which is converging and then diverging in shape, and nozzles carried by said partition 15 means which project across the last named chamber to a point well within the converging portion of said discharge passage and are focused on the axis thereof and which serve to convey the pumping fluid to the 20 discharge passage, the passages surrounding said nozzles serving to convey the fluid to be pumped and to convert pressure into velocity.
8. In an apparatus of the character described, the combination of a casing, means forming a partition dividing the casing into two chambers, one of which has an 25 opening for admitting pumping fluid,
- and the other an opening for admitting the fluid to be pumped, said last-named chamber 30 having also a discharge passage leading therefrom which is converging and then diverging in shape, and nozzles which project through and are adjustably mounted on said partition means and extend to a point well 35 within the converging portion of said discharge passage, said nozzles being designed to convert pressure into velocity and serving to convey the pumping fluid to the discharge passage, the passages surrounding said nozzles serving to convey the fluid to be pumped and to convert pressure into velocity.
9. In an apparatus of the character described, the combination of a casing, a partition member having openings therein 45 which divides the casing into two chambers, said openings being provided with seats, nozzles projecting through said openings having ball-shaped heads which fit against said seats, and a plate in fixed relation to said 50 partition member and having openings which receive the said ball-shaped heads to form universal pivots for said nozzles.

In witness whereof, I have hereunto set my hand this 13th day of July, 1915.

SANFORD A. MOSS.
